UNITED STATES PATENT OFFICE

156,632

TWIN PARKING METER

Eugene Kramer, Long Island City, N. Y.

Application February 25, 1949, Serial No. 1,092

Term of patent 14 years

(Cl. D52—3)

To all whom it may concern:

Be it known that Eugene Kramer, citizen of the United States of America, residing at Long Island City, in the county of Queens and State of New York, has invented a new, original, and ornamental Design for a Twin Parking Meter, of which the following is a specification, reference being had to the accompanying drawing, forming part thereof.

Fig. 1 is a top plan view of a twin parking meter, showing my new design.

Fig. 2 is a front elevational view.

Fig. 3 is a side elevational view.

The rear of the parking meter is substantially the same in appearance as the front.

I claim:

The ornamental design for a twin parking meter, as shown and described.

EUGENE KRAMER.
